(57) **CLAIM**

The ornamental design for graphical user interface for a computer monitor of an x-ray tomography scanner, as shown.

DESCRIPTION

FIG. 1 is a front view of graphical user interface for a computer monitor of an x-ray tomography scanner showing our new design, the broken line drawing a computer monitor of an x-ray tomography scanner is for illustrative purpose only and forms no part of the claimed design; and,
FIG. 2 is an enlarged front view of graphical user interface for a computer monitor of an x-ray tomography scanner.
